UNITED STATES PATENT OFFICE

CARL JASS, OF HORICON, WISCONSIN

CONTROL MEANS FOR EARTH PULVERIZING MACHINES

Application filed March 3, 1932. Serial No. 596,622.

This invention relates to control means for earth pulverizing machines.

An object of my invention is the provision of simple and efficient means for adjusting the pulverizing rollers of the machine.

Another object of the invention is the provision of simple and efficient means for adjusting the height of the seeding means.

A still further object of the invention is the construction of a simple and efficient hub for the primary tractor wheels of the machine.

Another object of my invention is to simplify the machine shown in my prior Patent No. 1,045,295, issued Nov. 26, 1912.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in side elevation of a mechanism constructed in accordance with the present invention, while

Figure 2 is a top plan view partly shown in section.

Figure 3 is a longitudinal sectional view taken on line 3—3, Figure 2, and looking in the direction of the arrows.

Figure 4 is an enlarged view in elevation of one of the bearing devices, while

Figure 5 is a top plan view of the same. Figure 6 is an enlarged view partly in section and partly in elevation of one of the seed tube adjusting devices.

Figure 7 is an enlarged view partly in elevation and partly in section of one of the hubs of the two master wheels, while

Figure 8 is a transverse sectional view taken on line 8—8, Figure 7 and looking in the direction of the arrows.

Figure 9 is a view in elevation of the lever devices.

Figure 10 is a sectional view taken on line 10—10, Fig. 3.

Figure 11 is a view in elevation of the frame bracing device.

Referring to the drawings by numerals, 1

designates the substantially rectangular frame, which is provided with a longitudinally extending center beam 2 which may be extended forwardly as at 3, Fig. 2 to greatly strengthen the machine. The frame 1 is 55 suitably supported upon the primary axle 4, to which is fixedly secured the master wheels 5 as hereinafter specifically described in connection with the hub structure shown in Figs. 7 and 8.

On the front axle 6 (Fig. 10) are mounted wheels 7, 7. Cables 8, 8 are secured at their outer ends in spaced relation to the axle 6; these cables are passed around pulleys 9 and run backward on the machine to the pulley 65 or drum 10 (Fig. 3) which is secured to the steering post 11, whereby the machine can be steered by the operator who may be sitting in the seat 12.

The curved braces 13 terminate at their outer ends in plate 14, which rests upon ball bearings mounted upon plate 15. A suitable king bolt 16 extends through plates 14 and 15 and axle 6, as well as tongue structure 17. The tongue structure 17 (Fig. 3) may pivot 75 slightly upwardly at 18, so that the jar will not be so great on the draft animals, whereby my machine is easier on the draft animals than if a solid or single piece tongue was used.

I preferably employ two pulverizing rollers 19; these rollers are specifically described in my co-pending application Serial No. 590,953, filed February 4, 1932. To vertically adjust each pulverizing roller 19, I 85 use at both ends bearing devices 20, as fully illustrated in Fig. 4. Each bearing device comprises a bracket 21 secured to the frame 1. Two vertical rods 22 extend at their upper ends through bracket 21. A plate 23 90 is fastened by lock bolts 24 on the lower end of rods 22. Plate 23 is provided with outwardly extending lugs 25. On each lug 25 is mounted pulley 26. Over pulleys 26 travels cable 27. This cable 27 is securely fastened at 28 (Fig. 2) to frame 1 with its outer end wound around drum 29. Drum 29 is provided with a suitable ratchet 30 engaged by pawl 31, whereby the bearing devices can be manually adjusted to control the depth 100

with respect to the operation of the pulverizing rollers on the ground. This general device is outlined in my prior Patent No. 1,045,295 but not the specific improved structure herein disclosed.

A slotted plate 32 is fastened at its lower end to plate 23 and in the slot of plate 32 is positioned the axle 33 of the pulverizing roller 19. On axle 33 is a bearing 34, at 10 each end of the axle. It is to be understood that I am describing only one of the four bearing devices 20, as each is a duplicate of the other. A plate 35 is also on the axle 33 (Fig. 4). Hoisting cable 36 is connected at 15 its lower end to plate 35; the opposite end of cable 36 is wound around drum 37; this drum is fixedly secured to two part shaft 38, so that when shaft 38 is rotated, the bearing device will be raised or lowered, depending 20 upon the direction of rotation of the shaft.

Shaft 38 is journalled upon standards 39 mounted upon frame 1. Two sprocket wheels 40 are used in constructing my mechanism, one on the outer end of each section 25 of the shaft 38. Around each sprocket wheel 40 passes chain 41; chain 41 is also mounted upon sprocket wheel 42; sprocket wheel 42 is rotated through main shaft 4 and the master wheels 5. Clutch device 43 is provided on each section of shaft 38 and is 30 operated through the medium of cable 44 connected to one of the several lever devices 45; these lever devices are positioned upon standard 46 contiguous to seat 12. By means 35 of the clutches 43, the shaft 38 can be operated at the will of the operator to raise or lower the pulverizing rollers 19 when desired. Also on the outer end of each section 40 of shaft 38 (constituting a two-piece single shaft across the machine) is positioned sprocket wheel 47; around sprocket wheel 47 travels chain 48. This chain 48 passes around sprocket 49 (Fig. 1); sprocket 49 is secured to shaft or axle 23 of the pulverizing 45 roller 19, whereby the pulverizing roller is rotated in one direction when the machine is drawn forward over the ground, but by means of ratchet 50, when the machine is backed, the sprocket wheels 47 will be 50 thrown out of mesh and the pulverizing rollers will be inoperative. For keeping each sprocket chain taut, I provide a chain tightening device 51, which comprises toothed wheel 52 mounted upon pivoted bar 53 (Fig. 51), which bar, through the action of spring 54 holds the toothed wheel 52 tightly against the chain 48. When the bearing devices 20 are raised sufficiently to lift the pulverizing rollers from contact with the ground, the 55 chain tightening devices 51 will still keep the chains relatively taut, but will yield readily when the pulverizing rollers are lowered in contact with the ground, for operating purposes.

There are a sufficient number of the lever

devices 45 to accommodate the necessary number of cables. For instance, the two cables 44 are connected to two of the lever devices 45, but as I do not claim anything specifically new in the lever devices and the 70 cable per se, I only mention the same in general terms. It is to be understood however that each lever device 45 is mounted upon shaft 55 carried by said standard 46. A drum 56 is fixedly secured to each lever device 45 as a part thereof, whereby the lever device operates the drum to wind its cable thereon sufficiently for operating the unit to which a cable is connected. An ordinary locking plate 57, fixedly secured to 75 shaft 55 is provided for each lever device to hold the same in a manually adjusted position.

I have found in actual practice that it is very desirable to brace frame 1 near its center, and consequently, I have invented a bracing frame device 58 comprising an upstanding auxiliary frame 59 having angular ends 60 secured upon the sides of frame 1 (Fig. 11). A horizontal bracing rod 61 80 extends across frame 59 and connects the sides. Braces 62 are connected at their upper ends to the central part of the auxiliary frame 59 and at their outer ends are connected to the sides of said frame 59 near 85 its angle ends 60. A vertical central rod 63 has a hook 64 on its lower end which fits over part of the central brace 2. The upper end of rod 63 is passed through the top of frame 59 and by means of nut 54, the rod 90 63 is held tightly in position.

Two covering rollers 65 are provided to assist in covering the seed that is planted through the medium of the planter attachment 66. This planter attachment comprises seed box 67 provided with a suitable number of chutes 68. A shaft 69 extends through the chute 68 and operates suitable seed discharging means of the seed box 67. This shaft 69 (Fig. 2) is driven by means 100 of sprocket chain 70 which passes over a suitable sprocket wheel 71, on shaft 69, and a suitable sprocket wheel 72 on main shaft 2. By means of a clutch device 73, operated 105 through cable 74, connected to one of the lever devices 45, the operator can throw in and out of mesh the clutch for controlling the discharge of seed from the seed box 67. On each chute 68 is placed a rubber hose 75 (Fig. 6). This hose extends into seed tube 110 76. Seed tube 76 is provided with a rearwardly extending lug 77, which lug is pivotally mounted at 78 on arm 79. Arm 79 is pivotally mounted at 80 upon depending bracket 81; bracket 81 is suitably secured 115 to the frame 1. A lug 82 is on arm 79 to which is connected at one end a spring 83, and the other end of the spring is connected to lug 84 on seed tube 76, whereby the seed tube is normally held in an operating po- 120

125 130

sition against web 85 of arm 79, but when the lower end of seed tube strikes a foreign object such as a stone, it will kick back to the dotted position "A", or further, to 5 allow the seed tube to pass over the obstruction without injury thereto, spring 83 returning the seed tube to its opposite position, as soon as the tube is relieved of its normal strain. Connected to lug 66, fastened to web 85, is lifting cable 87. This cable 87 is attached to a crank shaft 88; there are two cranks shafts 88 (Fig. 2) each provided with a suitable lever device 89, whereby the operator can raise or lower the 10 seed tube adjusting devices when desired.

The hub device 90 (Figs. 7 and 8) of each master wheel 5 comprises an inner conical section 91, which is provided with a plurality of longitudinally ribs 92. A hub 20 section 93 is placed over conical section 91 with ribs 92 fitting therein. A spoke unit 94 is fastened by key 95 upon axle 4 contiguous to the conical section 91 and hub section 93. The spoke unit 94 is provided 25 with large lugs 96 at opposite sides thereof, which are fitted in cut-out portions of notches 97 of the hub section 93. Sprocket wheel 42 is fitted tightly on hub section 93 against annular flange or shoulder 98. A 30 collar 99 is fitted on axle 4 tightly against the hub section 93. By means of this novel construction, a very powerful hub structure is produced which also greatly increases the life of the mechanism.

35 Referring to the bearing devices 20, and particularly to Fig. 4, on the rods 22, I place a bearing plate 100 against the bearing 34. On rods 22, against bracket 21, I place one or more detachable filler blocks 40 101. This loose block 101 is only in place when the machine is in operation in the field. Against filler block 101 is bearing plate 102. On rods 22 are coil springs 103. These 45 springs 103 bear at their ends against plates 100 and 102. By this structure, the pulverizing rollers are yieldably held against the ground, but the pressure exerted by springs 103 are admirably sufficient for permitting said rollers to perform excellent results.

50 Inasmuch as the general principle of several of the units of the present mechanism is disclosed in my prior Patent No. 1,045,295, reference may be had to said patent for a fuller understanding of this art, but the improvements disclosed in the present case make my old mechanism obsolete.

55 While I have described the preferred embodiment of my invention and illustrated 60 the same in the accompanying drawings, certain minor changes or alterations may appear to one skilled in the art to which this invention relates during the extensive manufacture of the same, and I, therefore, reserve the right to make such changes or

alterations as shall fairly fall within the scope of the appended claims.

What I claim is:

1. In a mechanism of the class described, the combination with a frame, of a plurality of bearing devices on said frame, each bearing device comprising a bracket attached to said frame, rods extending through said bracket, a bearing slidably mounted on said rods, springs engaging said rods and exerting pressure on said bearing, and an axle journaled in said bearing. 70

2. In a mechanism of the class described, the combination with a frame, of a plurality of bearing devices on said frame, each bearing device comprising a bracket attached to said frame, rods extending through said bracket, a bearing slidably mounted on said rods, a bearing plate engaging said rods and said bearing, coil springs around said rod and pressing at their lower ends against said bearing plate, a second plate on said rods and against the upper ends of said coil springs, filler blocks on said rods between said bracket and said last mentioned plate, and an axle journaled in said bearing. 80

3. In a mechanism of the class described, the combination with a frame, of a plurality of bearing devices on said frame, each bearing device comprising a bracket attached to said frame, rods extending through said bracket, a sliding bearing on said rods, springs on said rods and exerting pressure upon said sliding bearing, means carried by said rods for increasing the pressure of said springs upon said sliding bearing, and an axle journaled in said bearing. 95

In testimony whereof I hereunto affix my signature.

CARL JASS.
